UNITED STATES PATENT OFFICE.

HERBERT JOHN TOOGOOD, OF ELLAND, ENGLAND, ASSIGNOR TO ROBERT DEMPSTER & SONS, LIMITED, OF ELLAND, ENGLAND.

MEANS FOR UTILIZING THE RESIDUAL HEAT OF COKE PRODUCED IN VERTICAL GAS-RETORTS.

1,101,477.

Specification of Letters Patent. Patented June 23, 1914.

Application filed June 26, 1912. Serial No. 705,776.

To all whom it may concern:

Be it known that I, HERBERT JOHN Too-good, a subject of the King of England, residing at The Poplars, Elland, in the county 5 of York, England, have invented certain new and useful Improvements in Means for Utilizing the Residual Heat of Coke Produced in Vertical Gas-Retorts, of which the following is a specification.

10 There are in the British gas industry four known methods of charging vertical retorts, namely:—1. Intermittent, in which the whole charge is fed in at once and all emptied several hours afterward (say 12 hours); 2. 15 Continuous, in which coke is continuously withdrawn at the bottom and coal continuously enters at the top. 3. Semi-intermittent, in which every 3 or 4 hours a portion of the charge, say one third, is withdrawn, 20 and fresh coal immediately added at the top to fill up the retort again, so that after the first partial withdrawal the method has most of the characteristics of the continuous process. 4. Semi-continuous, in which coke 25 is continuously withdrawn at the bottom, but coal is intermittently fed at the top, say whenever about one-fourth of the charge has been withdrawn. This last method is open to the objection that a gradually increasing 30 space is left un-utilized at the top of the retort, until just before another partial charge is due the gas evolved lower down is damaged by having to pass through a large zone of radiant heat (instead of conducted heat). 35 The two latter methods (3 and 4) are sometimes included in the expression "semi-continuous", but the present invention only applies to methods 2 and 4.

This invention relates to gas retorts of the 40 type-known as "continuous" or "semi-continuous", and its objects are to cool the coke and to utilize as fully as possible the residual heat therein.

After the lower portion of the charge has 45 been fully carbonized, the resultant coke is of course at a high temperature, in fact much too hot to be dealt with by automatic extracting mechanism, and therefore requires to be cooled. It is desirable to 50 cover the residual heat from the coke and return it to the setting, and according to this invention the following apparatus is employed for this purpose:—Flues are arranged to inclose the retort extensions con-

taining the coke, through which flues primary air is circulated, and a water drip is arranged in connection with such flues. The water being evaporated, the air is thus caused to contain steam in definite proportions, these being regulated by the cock in 55 the water pipe, so as to insure a homogeneous mixture of air and steam throughout their entire volume, each being in the quantity best suited to the absorption of heat by this mixture from the coke, and the residual 60 heat of the latter being utilized in turning the water to steam, in facilitating its thorough intermingling with the primary air and in heating the resultant gaseous mixture. The temperature of 250° C. will usually be about that to which said mixture is thus subjected and the regulation of the supply of water as stated is to provide the greatest quantity of steam which the volume of air supplied will carry as a homogeneous 70 gaseous mixture, but no more than such quantity. The air and steam being thoroughly mixed and pre-heated are led to the producer. The cooling effect on the coke thus obtained, even considering the latent 75 heat in the water when so vaporized, might not be sufficient to extract the heat therefrom, especially in the center of the mass; I may therefore employ a U tube or other convenient means for supplying a water drip 80 on the center of the coke; the steam thus raised passes up through the charge and produces an addition of water gas. An auxiliary flue or flues may also be provided for the partial pre-heating of the secondary air 85 before passing to the regenerator, and where the secondary air is so heated, it is passed in the opposite direction to the primary air, so as to cool each retort extension to the same degree. The above flues will extract 90 as much heat as can be profitably utilized in the setting, but to further cool the coke and cause it to contract, so as to facilitate its handling by the discharging mechanism, I may employ a third chamber, connected to 100 the main flue and provided with a damper. By these means cold air would be circulated and the discharging mechanism assisted in doing its work.

In the accompanying drawings the figure 105 is a vertical section through the mouth-piece of a retort.

In the figure the reference numeral 2 in-

dicates the retort, 16 a downward extension thereof, 28 the discharging mouthpiece, 33 a discharging device. The extension 16 is wholly or partially surrounded by flues 15 and 20. The extension 16 of the retorts passing through these flues may if desirable be provided with ribs to increase their contact surfaces. The primary air enters the flue 20, and proceeds to the producer. The 10 secondary air passes through the flue 15 to the regenerator, which may be of any suitable type. A chamber 30 may also be provided for heating water or producing steam, the water being fed into this chamber 30 15 through the pipe 31. The pipe 31 may also feed the flue 20 for producing steam in connection with the primary air. The pipe for giving a water drip on the coke before discharge is shown at 32.

20 I am aware that it is not broadly new to heat primary air and secondary air together or separately before applying them to the retort, also that steam has sometimes been admitted with the primary air to the producer: and therefore do not broadly claim the same. But

What I do claim and desire to secure by Letters Patent is:

25 1. In a setting containing a plurality of continuously operated vertical gas retorts, each having a downward extension con-

structed to contain hot coke, the combination with a flue inclosing such downward extensions having a suitable outlet, and means for supplying air to such flue, of a regulatable 35 water drip device situated in such flue and in close proximity to the retort extensions, whereby steam in regulated proportions is produced in the flue itself by the residual heat of the coke in the retort extensions. 40

2. In a setting containing a plurality of continuously operated vertical gas retorts each having a downward extension constructed to contain hot coke, the combination with a primary air flue inclosing portions of such downward extensions and provided with a water drip device, of a secondary air flue inclosing other portions of such downward extensions and in which the air current is passed in the direction opposite to that of the air current in the said primary air flues, in order to cool each retort extension to the same extent, means for supplying air to the separate flues, and an outlet 45 for the heated air. 50

55 In testimony whereof, I have signed my name to this specification in the presence of two subscribing witnesses.
